UNITED STATES PATENT OFFICE

CHARLES LE G. FORTESCUE, OF PITTSBURGH, PENNSYLVANIA, ASSIGNOR TO WESTINGHOUSE ELECTRIC AND MANUFACTURING COMPANY, A CORPORATION OF PENNSYLVANIA.

TRANSFORMER.

1,129,469.

Specification of Letters Patent.

Patented Feb. 23, 1915.

Original application filed August 2, 1909, Serial No. 510,854. Divided and this application filed November 28, 1913. Serial No. 803,422.

To all whom it may concern:

Be it known that I, CHARLES LE G. FORTESCUE, a citizen of the United States, and a resident of Pittsburgh, in the county of Allegheny and State of Pennsylvania, have invented a new and useful Improvement in Transformers, of which the following is a specification, this application being a division of application Serial No. 510,854.

10 My invention relates to electrical apparatus, and it has special reference to the windings and insulation of transformers that are intended for use in connection with very high-voltage circuits.

15 The general object of my invention is to provide such a winding and such an insulating structure that the stress exerted by the voltage of the coils shall be properly distributed through the insulation with a view 20 to reducing the space occupied by, and the manufacturing cost of, a high voltage transformer or other similar apparatus.

25 In application, Serial No. 510,854, of which the present application is a division, I have disclosed and claimed a transformer comprising a plurality of spaced coils and an adjacent insulating sleeve or structure having conductors embedded in it and terminating adjacent to its ends, the coils being 30 connected to the corresponding opposite conductors.

35 It is the object of the present application to cover the combination of the coils with an insulating structure in which only a part of the conductors are connected to the coils, the conductors that are not connected to the coils extending beyond the coils. The potentials of certain of the conductors, therefore, are fixed by the connections to the 40 coils, whereas, the potentials of the remaining conductors are fixed by condenser action.

45 My invention is illustrated in the accompanying drawings, Figure 1 of which is a view, in side elevation and in section, of a transformer constructed in accordance therewith, and Fig. 2 is a similar view of a modified form of the transformer.

50 The transformer illustrated in Fig. 1 comprises a substantially rectangular core 1, a low-potential winding 2 that is divided into two groups of coils which surround two opposite legs 3 and 4 of the core 1 and are separated therefrom by insulating sleeves 5, a

primary winding composed of two groups 6 and 7 of relatively flat coils, insulating sleeves 8 and 9 located on the respective core legs between the low and high-potential windings, and insulating carriers 10 and 11 that insulate the high-potential windings from each other and from other adjacent parts. The core legs 3 and 4 may be of any suitable form but are preferably cruciform in cross section, in order to economize space and to reduce the mean length of turn in the winding.

65 The insulating sleeves 8 and 9 are similar to each other, and each preferably comprises a plurality of cylinders 13 of conducting material and insulating cylinders 14 which alternate therewith. The conducting cylinders are of graded lengths, the longer ones being adjacent to the low-potential winding, and the shorter ones adjacent to the high-potential winding. The sleeves 10 and 11 are also similar to the sleeves 8 and 9, and 70 the conductors embedded therein are also similarly arranged with respect to the coils of the high-potential winding.

75 The centrally located coil 17 upon the core leg 3 is connected to a high-potential 80 external circuit (not shown) by means of a conducting lead 15 which extends through a terminal bushing 16. From this coil, a circuit is continued through the conducting cylinder 13* of largest diameter of the sleeve 8 to one terminal of an adjacent coil 18, the other terminal of which is connected through the conducting cylinder 10* of smallest diameter of the barrier 10 to one terminal of the coil 19 which is located upon 90 the other side of the coil 17. Circuit is similarly continued through coils 20, 21, 22, 23, 24, 25, 26, 27 and 28, the free terminal of coil 28 being grounded or connected to one terminal of a coil 29 of the group 7. 95 The circuit is continued through the coils of this group in the same way as it was completed through the coils of the group 6, but in the reverse order, the lead 30 being finally brought out through a terminal bushing 31. 100

105 By interconnecting the coils through the conducting cylinders which constitute parts of the insulating sleeves, the potentials of the said conductors are fixed and the strains imposed upon the insulation are distributed in a manner that is determined by the law

2
or rule according to which the potentials of the conductors are fixed; for instance, the potentials of the embedded conductors may be fixed at such values as to produce a substantially uniform distribution of potential throughout the insulating structures, or they may be fixed so as to cause the distribution of the potential to follow the logarithmic law, which represents the distribution of potential that would exist if the inner and outer conducting cylinders were of infinite length.

It will be noted that the insulating sleeves surrounding the core legs extend somewhat beyond the ends of the two groups of coils, and that the innermost conducting cylinders are not connected to the coils. The potentials of the said innermost conducting cylinders are, therefore, determined by condenser action between adjacent pairs of cylinders. This arrangement is particularly advantageous when the potentials of the end coils of the groups are comparatively high with respect to that of the core structure.

The low-potential winding may, if desired, be divided into four parts, as shown in Fig. 2, two of the parts being respectively disposed outside of the two groups of high-potential windings, and the remaining parts being located inside thereof, as in Fig. 1. The advantages obtained from this arrangement are well known.

When both ends of each of the transformer winding groups 6 and 7 are maintained at a relatively high potential above the ground, the terminals 6^a and 7^a, which are interconnected, are carried away from the core member through bushings 6^b and 7^b, as shown in Fig. 2, in order to avoid grounding.

I claim as my invention:

1. In an electrical device, the combination with a plurality of coils, of an adjacent insulating structure comprising interleaved insulating and conducting members, the potentials of certain of the conducting members being conductively determined and those of the remaining members being determined by condenser action.

2. In an electrical device, the combination with a plurality of coils, of an adjacent insulating structure comprising interleaved insulating and conducting members, the potentials of certain of the conducting members being determined by condenser action, the portion of the structure embodying the latter conductors extending beyond the coils.

3. In an electrical device, the combination with a plurality of coils, of an adjacent insulating structure comprising interleaved insulating and conducting members, a part only of the conducting members being connected to the coils.

4. In an electrical device, the combination with a plurality of coils, of an adjacent in-

sulating structure comprising interleaved insulating and conducting members, a part only of the conducting members being connected to and included in circuit with the coils.

5. In an electrical device, the combination with a plurality of coils, of an adjacent insulating structure comprising interleaved insulating and conducting members, a part only of the conducting members being connected to and included in circuit with the coils, and the portion of the structure embodying the remaining conductors extending beyond the coils.

6. An electrical device comprising a plurality of coils, an adjacent insulating structure having its end portions inclined relatively to the axis of the coils, and spaced conductors terminating adjacent to the inclined portions of the insulating structure, a part only of which are connected to the coils.

7. An electrical device comprising a plurality of coils, an adjacent insulating structure having its end portions inclined relatively to the axis of the coils, and spaced conductors terminating adjacent to the inclined portions of the insulating structure, those nearest the coils being connected thereto, while the remaining conductors are not connected thereto.

8. An electrical device comprising a plurality of coils, an adjacent insulating structure having its end portions inclined relatively to the axis of the coils, and spaced conductors terminating adjacent to the inclined portions of the insulating structure, a part only of which are connected to the coils, the said conductors being respectively opposite to the coils to which they are connected.

9. An electrical device comprising a plurality of coils, an adjacent insulating structure having its end portions inclined relatively to the axis of the coils, and spaced conductors terminating adjacent to the inclined portions of the insulating structure, a part only of which are connected to the coils, the said conductors being respectively opposite to the coils to which they are connected, and the portion of the structure embodying the remaining conductors extending between the coils.

10. An electrical device comprising a plurality of coils, an adjacent insulating structure having its end portions inclined relatively to the axis of the coils, and spaced conductors terminating adjacent to the inclined portions of the insulating structure, a part only of which are connected to the coils, the portion of the structure embodying the remaining conductors extending beyond the coils.

11. An electrical device comprising a plurality of coils, an adjacent insulating structure having its end portions inclined relatively to the axis of the coils, and spaced

conductors terminating adjacent to the inclined portions of the insulating structure, only the conductors that terminate adjacent to the intermediate portion of the structure being connected to the coils.

12. An electrical device comprising a plurality of coils, an adjacent insulating structure having its end portions inclined relatively to the axis of the coils, and spaced 10 conductors terminating adjacent to the inclined portions of the insulating structure,

only the conductors that terminate adjacent to the intermediate portion of the structure being connected to and included in circuit with the coils.

15

In testimony whereof, I have hereunto subscribed my name this 18th day of Nov. 1913
